ELIMINATION OF DISTORTION IN
ELECTRON DISCHARGE DEVICESClarence W. Hansell, Port Jefferson, N. Y., assign-
or to Radio Corporation of America, a corpo-
ration of DelawareApplication May 21, 1931, Serial No. 538,958
Renewed January 21, 1937

13 Claims. (Cl. 179—171)

This invention has as its principal object the provision of methods and means for the elimination of distortion in electron discharge device amplifiers and especially the distortion due to the drooping of the characteristic curve of an amplifier caused by grid rectification.

A linear characteristic for the output of an electron discharge device amplifier relative to its input may readily be obtained when the output of the amplifier is kept within approximately half of its commercial rating for high efficiency continuous wave operation. However, beyond that point, the ratio of output to input for the amplifier is no longer a constant and the characteristic curve which represents the ratio between the input and output of the amplifier droops beyond the half rating value. In the case of telephonic communication or multiplex communication, this distortion limits a transmitter output to approximately half of what its rated output would be for continuous wave telegraphy, making a great reduction in power and transmitter efficiency as well as increasing cost of construction and operating expenses for transmission of modulated signals of desired power where the amplitude of the output must faithfully follow the wave shape of the modulation energy.

The drooping characteristic of an amplifier may be attributed to several causes, the most important of which is decrease in effective grid resistance starting with grid rectification.

Relative to other causes of distortion, such as saturation of vacuum tubes used for an amplifier, grid rectification presents a difficult problem inasmuch as it causes a discontinuous break in the characteristic amplification curve of the amplifier. That is, in the case of saturation, the saturation characteristic of tubes is fairly continuous and can be balanced out to a great extent by adjusting earlier amplifier stages so that they produce a curvature opposite to the saturation curvature to be corrected.

Heretofore, in order to reduce the effect of grid rectification, the input circuit of the amplifier has been artificially loaded with resistances so that the increased losses produced by the grid rectification are small in comparison with the losses throughout the loaded input circuit. Consequently, the change in effective grid resistance, due to rectification, has a relatively small effect upon the voltage regulation of the input circuit and, therefore, upon the curvature of the amplifier characteristic.

But such a loading method, in order to be prac-

tically effective, necessitates a large ratio between radio frequency losses in the input or grid excitation circuit relative to the grid losses, entailing a marked reduction in power, efficiency and amplification in the amplifier. As a result of this, for a given output, an increased number of stages are needed having concomitant thereto, disadvantages of increased construction and operating costs to say nothing of increased unreliability of an installation.

To overcome the foregoing difficulty is another object of the present invention and according to it, it is accomplished by feeding energy to an amplifier having an undesired characteristic through a plurality of electron discharge devices. One of the devices is so designed or adjusted that it continually feeds power into the amplifier, the ratio of the power fed to the power supplied to the device being substantially constant. However, according to the present invention, another of the coupling electron discharge devices is so designed or so adjusted or biased that it delivers little or no output until the excitation of the power amplifier is such that its characteristic begins to droop. From that time on, the last referred to electron discharge device will add more and more power to the output of the first electron discharge device thereby correcting the droop in the power amplifier characteristic. As a result of this structure a power amplifier is made capable of giving a much higher output before the distortion limit is reached.

If desired the two coupling electron discharge devices may be mounted within a single evacuated envelope or may be combined into one set of elements different areas of which have different characteristics. For example, one portion of the area of a three element vacuum tube may have a coarse grid and another area a fine grid such that the area with the fine grid does not begin to have an electron discharge until the conditions are reached where a correction of the characteristic is desired. Tubes having different spacings between portions of the elements may be used or there may be differences in both the grid mesh and the spacings.

To more fully understand the present invention, reference is made to the accompanying drawings which, it is to be clearly understood, is given solely by way of illustration of the present invention, and wherein

Figure 1 is a graph illustrating the drooping characteristic of a commercial power amplifier, the droop beginning at approximately 50% of its rated power output.

Figure 2 illustrates a system for correcting the droop of the amplifier whereby its linear characteristic is continued past the point where ordinarily drooping would occur due to grid rectification.

Figure 3 is a modification of the invention illustrated in Figure 2, and,

Figure 4 shows the effect upon the characteristic which is obtained by paralleling or using in 10 a single pushpull amplifier stage, in any ordinary amplifier design, two commercial tubes having different amplification constants but like circuit and potential adjustments.

Turning to Figure 1, the solid line 2 indicates 15 the relation between the power output of a commercial power amplifier and the input voltage applied thereto. From inspection it is clear that at point 4, where grid rectification occurs, the characteristic of the amplifier is no longer a 20 straight line but becomes curved, resulting in modulation distortion and, in the event that the amplifier is used in a transmitter for telephone or multiplex telegraph communication purposes, this will tend to limit the amplifier output, requiring, for a given strength of signal, additional 25 amplifiers, thereby increasing the cost of installation as well as operating costs therefor.

To operate an amplifier such that it will have a straight line characteristic beyond the point 30 where grid rectification occurs, it is proposed, according to the present invention, to vary the input to the amplifier such that the curvature thereof is compensated and so that, referring to Figure 1, the characteristic of the amplifier continues along the dotted straight line 6 beyond the point where grid rectification occurs.

Referring to Figure 2 which illustrates apparatus for carrying into effect the foregoing desired result, undulatory currents from a suitable 40 source 8 are fed to an amplifier 10 here in the form of a screen grid tube with a tuned output circuit and thence through electron discharge devices 12, 14, to a power amplifier 16 comprising pushpull connected capacity neutralized electron 45 discharge devices 18, 20. The screen grid of tube 10 is supplied with direct current by a resistance 11 connected to the direct current potential circuit for the anode of 10. A bypass condenser 3 may be connected between the screen grid and 50 cathode of 10.

To neutralize or correct the drooping characteristic of the power amplifier 16, tube 14, by virtue of its coupling through lead 22 to amplifier 10 is given a higher excitation than tube 12; but, 55 its control electrode 24 is more negatively polarized or biased from potentiometer 26 and tapping conductor 28 so that it is cut off or rendered non-conductive until the output of amplifier 16 begins to droop as illustrated by point 4 of Figure 60 1. The excitation voltage amplified by tube 10 at which the output of amplifier 16 starts to droop is sufficient to overcome the negative bias on the grid of tube 14 and the output of electron discharge device 14 is added to that of tube 12 and their combined outputs give a greater excitation to amplifier 16 than tube 12 alone could give in an increasing proportion. In this manner, the excitation of amplifier 16 will be increased more than proportionally beyond point 65 4, as a result of which, over a considerable range beyond that where normally grid rectification occurs, the output of power amplifier 16 relative to the output from amplifier 10, is a straight line.

In order to prevent the effects of interelectrode 70 feed back, tubes 10, 12 and 14 may be capacity

neutralized or as illustrated they may be of the screen grid type, the screen grids being suitably biased by the action of resistors 11 connecting the respective screen grids to the respective anode polarizing leads for the tubes. I prefer to use the screen grid tubes because, over the operating range their plate potential variations have less effect upon the anode currents than is the case with three electrode tubes and the effect of tube 14 upon the radio frequency anode voltage of tube 12 has less tendency to reduce the output current of tube 12. Consequently the two output currents remain more unaffected by one another and tend each to add its portion of output current in the manner desired. The screen grids, 15 of course, have been grounded for radio frequency potentials by the use of by-pass condensers illustrated diagrammatically at 13 and, radio frequency flow through potentiometer 26 is prevented by the action of radio frequency chokes 20 15.

Rectangle 8 not only diagrammatically represents a source of undulatory current but indicates as well and diagrammatically also, means for modulating the energy from the source. In the event that it is desired to introduce modulation into a stage immediately preceding the power amplifier and yet have a straight line characteristic for the same beyond the point where grid rectification occurs, the arrangement shown in 30 Figure 3 may be utilized to good advantage.

In Figure 3, energy from a source 30, of undulatory electrical currents, is fed to a pair of screen grid electron discharge devices 32, 34. Modulating energy of relatively low frequency 35 from a source 36 is fed to a modulation amplifier 38 whose anode together with the anodes of screen grid tubes 32, 34 is fed through a choke coil 40 with suitable anode polarizing potentials supplied by lead or conductor 42.

The control electrode 44 of screen grid tube 32, the screen grid 46 through the action of resistance 48 coupling it to the anode potential source, and the anode of tube 32 are so polarized as to give a radio frequency output current 45 substantially proportional to the applied input voltage over the desired range of operation.

Tube 34 differs in polarization in that the screen grid 50 thereof is biased through a potentiometer 52 so that it has a negative or low positive potential thereon until modulation of the anode voltage by the high signal on tube 38 makes it more positive. This takes place at and after the time at which grid rectification occurs to cause distortion in the power amplifier 54. In other words, there is little output from tube 34 until the droop of the amplitude characteristic of the power amplifier designated in Figure 1 by point 4 is reached. At that time tube 34 will have higher potentials on its screen grid and anode and will begin to add power to the output of tube 32 and, by suitable adjustment of circuit elements, will compensate for the curvature in the amplifier characteristic of power amplifier 54 which may consist of one or more amplifier stages.

Rather than polarize electrodes of a plurality of tubes to different values such that the output of one adds to the output of the other only after a predetermined operating point is reached, the same result may be obtained by combining two tubes having different characteristics or in other words, different amplification constants. These different characteristics may be due to any number of reasons, for example, by using different 70 75

grid mesh and possibly different spacings between control electrodes such as the grids and cathodes or filaments. Two such tubes used in a single or the same amplifier stage either in parallel or in opposite sides of a pushpull circuit, would give a desired characteristic such as disclosed heretofore.

Thus, referring to Figure 4, a tube having the characteristic given by curve 1a may be combined either in pushpull or in parallel with a tube having the characteristic indicated by the solid line 3a of Figure 4. The resultant characteristic of the combination of tubes polarized alike but having different amplification characteristics as indicated would be given by the dotted curve 4a which, of course, has a desired output characteristic relative to the input.

This arrangement may be extended not only to a pair of tubes having different characteristics, but to groups of tubes of differing characteristics whereby the combination results in a more desirable characteristic. To provide an added adjustment, the different tubes or groups of different tubes may be polarized differently.

It should be clear that although only two schemes have been illustrated and described for carrying out the foregoing thought of having an auxiliary tube added to the output of another tube only after a certain output amplitude is reached and then in such proportion as to obtain the correction of an unfavorable amplifying characteristic, many other detailed circuits, in the light of the foregoing teachings, may readily be set up by those skilled in the art, and consequently the present invention is not to be limited in scope by the modifications shown but is to be given a scope commensurate with that indicated by the appended claims.

Having thus described my invention, what I claim is:

1. In apparatus for the amplification of undulatory electrical currents, a thermionic amplifier having a drooping plate current grid potential characteristic, an electron discharge device connected to said amplifier for supplying signal energy to be amplified to said amplifier, and an auxiliary electron discharge amplifying device for supplying additional signal energy to said amplifier to be amplified when the amplifier operates on the drooping portion of its characteristic curve.

2. In a system for the amplification of undulatory electrical currents, a source of undulatory electrical currents, an amplifier for amplifying said currents, an electron discharge device for feeding currents from said source to said amplifier, and an auxiliary electron discharge device for feeding additional currents from said source to said amplifier during the time that the amplifier is operated on a portion of its characteristic which normally droops due to grid rectification whereby said amplifier continues to have a linear output with respect to input for large input values.

3. In apparatus for the amplification of undulatory electrical currents, a source of undulatory electrical currents, an amplifier for amplifying currents from said source, a pair of electron discharge devices coupling said source and said amplifier, one of said electron discharge devices continually feeding energy from said source to said amplifier and the other of said electron discharge devices feeding energy from said source to said amplifier after the output of said amplifier

would normally droop due to grid rectification whereby said amplifier continues to have a linear output with respect to input for large input values.

4. In apparatus for the amplification of undulatory electrical currents, a source of currents to be amplified, an amplifier, having a successively linear and drooping characteristic, for amplifying the currents, a pair of pushpull connected electron discharge devices for coupling the source to said amplifier, and means for biasing one of said electron discharge devices to give a relatively small output during operation on the linear portion of said amplifier, and to give an increased output, during operation on and to compensate for, the drooping portion of said amplifier characteristic.

5. In a system for the amplification and transmission of undulatory electrical currents, a source of undulatory electrical energy, a pair of pushpull connected electron discharge devices coupled to said source, said pair of devices having their cathodes connected together, their control grids connected in phase opposition and their anodes connected in phase opposition, an amplifier coupled to said pushpull connected electron discharge devices, and means for preventing flow of energy through one of said pushpull connected electron discharge devices until the output of said amplifier reaches a predetermined value.

6. In apparatus for the amplification of undulatory electrical currents, a source of undulatory electrical energy, an electron discharge device coupled to said source, an amplifier coupled to said electron discharge device, said electron discharge device feeding at all times energy from said source to said amplifier, another electron discharge device coupling said source and said amplifier, said last mentioned electron discharge device being coupled to said source so as to have greater excitation than said first mentioned electron discharge device, and means for biasing said last mentioned electron discharge device so that it feeds energy from said source to said amplifier only after the output of said amplifier has reached a predetermined value.

7. In apparatus for the amplification of undulatory electrical currents, a source of undulatory electrical currents, an amplifier for amplifying the currents, a pair of electron discharge devices coupling said source and said amplifier, said pair of devices having their output electrodes connected to a common output circuit, which circuit forms the input circuit for said amplifier, and means including a source of direct current potential for biasing one of said electron discharge devices so that it does not feed energy from said source into said amplifier until after a predetermined output of said amplifier is reached, at which time the output of said biased electron discharge device is added to the output of the other of said pair of electron discharge devices to cause an increased input to said amplifier.

8. In a system for amplifying alternating currents, a source of alternating currents, an amplifier for amplifying the alternating currents, and means for coupling said source to said amplifier, said coupling means comprising a pair of electron discharge devices having their output electrodes coupled to said amplifier and their input electrodes connected to said source of alternating current, said connection being such that the input electrodes of one of said electron discharge devices is subjected to higher amplitude alternating potentials from said source than the other.

9. An amplifying system for amplifying alter-

- nating currents comprising a source of alternating currents and a coupling system for coupling the source to said amplifier, said coupling system comprising a pair of electron discharge devices each having an anode a cathode a control electrode and a screen grid, a common alternating current circuit connected to the anodes of the devices forming said coupling system, means for subjecting one of said screen grids to a more positive unidirectional potential than the other and, means for feeding energy from said common circuit to said amplifier.
10. In combination, a source of alternating currents to be amplified, a first electron discharge device amplifier coupled to said source, said discharge device having a tuned output circuit, a second high power electron discharge device amplifier and means coupling the tuned output circuit of said first mentioned discharge device amplifier to said high power electron discharge device amplifier, said means comprising a pair of electron discharge devices having like electrodes subjected to different uni-directional polarizing potentials and having input electrodes effectively coupled to points of different alternating potentials on the tuned output circuit of said first mentioned amplifier.
11. In combination, a source of alternating currents to be amplified, a high power amplifier for amplifying currents from said source and, means for coupling said source to said high power amplifier, said means comprising a pair of electron discharge devices each having input electrodes and output electrodes and an additional electrode for preventing inter-electrode feedback, high frequency circuits connected to said input and output electrodes so that said electrodes fluctuate in phase opposition, and means for subjecting said

additional electrodes to different uni-directional polarizing potentials whereby one of said devices does not feed appreciable energy into said power amplifier until a predetermined amplitude input to said device is reached.

12. In a transmitting system, a high frequency circuit, means for causing modulated high frequency waves to flow in said circuit, a pair of vacuum tubes in said circuit, means for subjecting the input electrodes of the tubes of said pair of tubes to relatively different direct current potentials, means for subjecting the control electrodes of said tubes of said high frequency circuit to modulated radio frequency potentials of different values, the value of the radio frequency potential supplied to the grid of the tube having the least positive direct current potential being greater than the value of the radio frequency potential supplied to the grid of the other tube, a common output circuit for said tubes, and means for combining the outputs of said tubes in said common output circuit.

13. In an amplifying system, a source of alternating currents to be amplified, a power amplifier to amplify currents from said source, means for coupling said source to said power amplifier, said means comprising a pair of electron discharge devices having a common high frequency input circuit and a common high frequency output circuit, means for subjecting electrodes of said devices to uni-directional potentials such as to render one substantially less conductive than the other, and means for subjecting said electron discharge device of lesser conductivity to higher alternating potential from said source relative to the potential supplied from said source to the other device of said pair of devices.

CLARENCE W. HANSELL.
